UNITED STATES PATENT OFFICE.

PERCY R. OWENS, OF NEW YORK, N. Y.

AUTOMATIC CURRENT-CONTROLLING DEVICE

SPECIFICATION forming part of Letters Patent No. 746,140, dated December 8, 1903.

Application filed April 18, 1903. Serial No. 153,152. (No model.)

To all whom it may concern:

Be it known that I, PERCY R. OWENS, a citizen of the United States, residing at New York city, New York county, New York, have invented certain new and useful Improvements in Automatic Current-Controlling Devices, of which the following is a full, clear, and exact description.

My invention relates to automatic current-controlling devices for charging storage batteries; and it consists in various means whereby the charging of the storage battery is controlled, so that the potential of the current applied gradually increases automatically and so that the battery when it is fully charged is automatically disconnected from the supply-circuit, and also in means for determining the time for the automatic interruption of the supply-circuit, and has for its object to provide a novel means for attaining these ends.

The following is a description of an apparatus embodying my invention, reference being had to the accompanying drawings, in which—

25 Figure 1 represents an elevation of the apparatus with the battery shown diagrammatically. Fig. 2 represents a modification of one of the elements thereof. Fig. 3 represents, on a slightly-enlarged scale, a side elevation of one of the elements thereof, showing parts in section.

Referring more particularly to the drawings, A is the base on which the parts are mounted.

35 B C are the binding-posts to which the terminals of the supply-circuit are connected.

D E are the binding-posts to which the terminals of the storage battery F are connected when it is desired to charge the same.

40 G is a series of contact-plates corresponding to a graduated series of pressures. In Fig. 1 these plates are connected by resistances H, so as to form a rheostat.

I is a contact-arm, weighted at I' and pivoted at J and bearing upon the contacts G. This arm I is normally pressed downward by a spring K, which acts to move the arm slowly against the opposition afforded by the dashpot L. The arm I has a segment M, having 50 notches m, equal in number to the contact-plates G. Against the segment M bears a detent N, to whose arm at the point O a retrac-

tive spring P is attached. A solenoid-core Q is also attached to this arm at the point O and is acted upon by the solenoid R. One terminal of this solenoid is electrically connected to the arm I of the point J. The other terminal of this solenoid is connected to the stationary contact S, with which the movable contact S' of the circuit-breaker S² engages. 55

T is a second stationary contact, with which the movable contact T' of the circuit-breaker engages. The contacts S' and T' are electrically connected by the cross-bar T² and carried by an arm U, pivoted at the point u. Against the arm U a spring U' bears, normally tending to force the contacts S' and T' out of engagement with contacts S and T and the contact 11 out of engagement with contacts 12 and 13. 70

V is a magnetic detent pivoted at v and retracted by a spring V', so as to engage with a projection W upon the arm U.

X and X' are two electromagnets, either of which when sufficiently energized will act 75 upon the detent V, so as to overcome the spring V' and draw the detent out of engagement with the projection W, permitting the arm U to be thrown outward by the spring U. The electromagnet X' is interposed in the circuit which passes from the battery-terminal E to the solenoid R, the arm I, and contact-plates G, the result being that if the current flowing to the battery F is at any time excessive the magnet X' will become so energized 80 as to operate the detent V to release the arm U. The electromagnet X is interposed in a circuit passing from the stationary contact S to the terminal D, which is connected to the terminal C. This circuit is normally interrupted at the point Y, the part connected to the terminal of the electromagnet X being connected to a stationary contact 1, while the part connected to the terminal D is connected to a movable contact 2, carried by an 85 armature 3, pivoted at the point 3' and retracted by a spring 4.

5 is an electromagnet, one terminal of which, 6, is connected with the battery terminal E, while the other terminal, 7, is connected with 100 the rheostat 8, the arm 9 of which is electrically connected with the battery-terminal D through the terminal C and conductor 10. The main terminal C and the battery-termi-

nal D, being electrically connected by a conductor 10, in effect form but one terminal. The magnet 5 and the rheostat 8 are therefore connected in shunt across the battery-
 5 terminals D and E. The effect of this is that should the counter electromotive force of the battery F rise to such an extent as to force sufficient current through the magnet 5 to energize the same sufficiently to attract the armature 3 the contacts 1 and 2 will be brought together and the circuit completed from the terminal D through the magnet X, contacts S S' T T' to the terminal E, and also from C to D, through X R, and I to B. The magnet
 10 X is so wound that when this happens it is sufficiently energized to attract the magnetic
 15 detent V and release the arm U, interrupting the charging-circuit by interrupting the circuit at the contacts S S' T T'. The circuit
 20 between the contact 6 and the binding-post E is made and broken by the movable contact 11, carried by the arm U, the terminal 6 being electrically connected with the stationary contact 12 and the terminal E being electrically connected with the stationary contact 13, so that when the switch U is opened the electromagnet 5 is also deenergized. This permits the contacts 1 and 2 to be separated and deenergizes the magnet X.
 25 The purpose of the rheostat 8 is to enable the resistance in the circuit containing the magnet 5 to be adjusted. It is a convenient means of adjusting the charging limit according to the temperature, the fact being
 30 that the resistance of the storage battery decreases with the temperature. In order, therefore, to have the battery fully charged before the automatic circuit-breaker operates, resistance is thrown into the circuit of
 35 the magnet 5 by the rheostat 8 to make up for the decrease in resistance due to a fall in the temperature and removed when the temperature of the battery rises.
 40

In operating the device the storage battery
 45 to be charged is first connected to the terminals D E. The contact-arm I is then moved upward until it engages the stop i, at which time it rests upon the first of the contacts G corresponding to the lowest pressure. The
 50 circuit-breaker S² is then closed, connecting the terminals S S' and T T' and also the contacts 11, 12, and 13. This completes the main circuit B G I J R S S' T T' E, battery F, and terminals D C, also completing the shunt-circuit D C, rheostat 8, magnet 5, contacts 11,
 55 12, and 13, and terminal E. The charging of the battery then begins, the electromotive force impressed upon its terminals being that corresponding to the first member of the series of contacts G. As the counter electromotive force of the battery rises the current supplied to it and passing through the solenoid R is reduced in strength. When this current is reduced in strength to such an extent that the spring P overcomes the attraction of the solenoid R, the detent N is released
 60 from the first notch m in the segment M, per-

mitting the spring K to force the arm I downward toward the next succeeding contact G. Upon reaching this contact the counter electromotive force corresponding thereto is impressed upon the battery-terminals and the resultant current so energizes the solenoid R as to overcome the spring P and force the detent N into engagement with the next succeeding notch m upon the segment M. The arm I is then held in contact with the second contact until the counter electromotive force of the battery has increased to such an extent that it reduces the current through the solenoid R to such an extent that the spring P again overcomes the pull due to the solenoid and acts to move the pawl N out of engagement with the second notch in the segment M and permit the arm I to move until the third notch m is presented and engaged by the detent. This operation is continued until the arm I has moved over the entire series of contacts G or until the battery F is fully charged. Whenever the battery F is fully charged, whether that be after the arm I has passed over all the contacts of the series G or at any time prior thereto, the counter electromotive force of the battery F will have increased to such an extent as to energize the magnet 5 sufficiently to enable it to attract the armature 3, so as to bring the contacts 1 and 2 into engagement. Whenever this occurs, the magnet X is shunted across the main supply-circuit terminals B C and also the battery-terminals D E, with the result that it is energized and attracts the armature V, so as to release the arm U, which then is moved by the spring U', so as to break the supply-circuit to the battery and interrupt the circuit through the magnet 5. The interruption of the circuit through the magnet 5 permits the spring 4 to break the circuit of the magnet X at the points 1 and 2. All the parts are thus out of circuit until it is desired to charge another battery. When another battery is placed in circuit, the arm I is raised and the circuit-breaker closed. The resistance of the circuit in which the magnet I is located is adjusted by the rheostat 8 to compensate for temperature changes or to determine the charging limit of any battery that may be connected in circuit, as heretofore explained. In case the current delivered to the battery is too strong the magnet X' acts upon the detent V to release the arm U, which then interrupts the various circuits, as stated above. By using the auxiliary magnet 5 the detent V is not subject to the cumulative effect of the shunt and series magnets X X', except when the contacts 1 2 are in engagement and the magnet X energized. The magnet X when energized is strong enough to release the detent V independently of the magnet X' whatever may be its condition, so that the action of the two magnets is practically independent and at all times unaffected by each other.

Instead of using resistances H in order to

obtain different pressures at the several contact-plates of the series of contacts G the contact-plates may be connected to sources of counter electromotive forces varying by the desired amounts. I have shown this arrangement in Fig. 2, in which the contact-plates G are connected to bus-bars of different pressure, the bus-bar 20 having, for instance, a pressure of ninety volts and being connected to the first of the series of contact-plates G, the bus-bar 21 having a pressure of, say, one hundred and twenty volts and connected to the last of the series of contact-plates G, the intermediate bus-bars having gradually-varying pressures and being connected to respective intermediate contact-plates. In the arrangement shown in Fig. 2, as well as that shown in Fig. 1, the contacts G have gradually-increasing pressures, due in one case to gradually-decreasing resistance and in the other case to connection with bus-bars.

My invention admits of various changes and modifications and the substitution of equivalent devices for elements shown, and I therefore do not wish to be limited to the precise form of apparatus shown, but regard as within my invention devices in which such changes and substitutions may be embodied.

30 What I claim is—

1. In combination a source of supply, a battery to be charged, a series of contact-plates connected so as to have gradually-increasing pressures, a contact device moving along said contacts and means for mechanically engaging said contact device and retaining it on any contact-plate until the counter electromotive force of the battery has reached a degree corresponding thereto, and then automatically moving it to the next contact-plate.
2. In combination a source of supply, a battery to be charged, a series of contact-plates connected so as to have gradually-increasing pressures, a contact device moving along said contacts, an electromagnetic device in series with said battery, and a detent controlled thereby and mechanically engaging with said device to retain it on any contact until the counter electromotive force has reached a degree corresponding thereto.
3. In combination a source of supply, a battery to be charged, a series of contact-plates connected so as to have gradually-increasing pressures, a contact device moving along said contact-plates, an electromagnetic device in series with said battery, and a detent controlled thereby and engaging with said device to retain it on any contact until the counter electromotive force has reached a degree corresponding thereto and means for braking the movement of said device.

4. In combination a source of supply, a battery to be charged, a series of contact-plates connected so as to have gradually-increasing

pressures, a contact device moving along said contact-plates, means for mechanically engaging said contact device and retaining it on any plate until the counter electromotive force reaches a degree corresponding thereto, and a circuit-breaker acting to automatically open the circuit in case the current supplied becomes abnormal.

5. In combination a source of supply, a battery to be charged, a series of contact-plates connected so as to have gradually-increasing pressures, a contact device moving along said contact-plates, a circuit-breaker in the supply-circuit, said circuit-breaker having a contact-arm, a spring normally tending to open the same, and a detent, and means for releasing said detent, said means responding to either an abnormal current or an abnormal electromotive force.

6. In combination a source of supply, a circuit therefor, a storage battery connected thereto, a circuit-breaker in said supply-circuit, a magnet in said supply-circuit acting to operate the breaker when the current is abnormal, a circuit in shunt to said battery and an electromagnet controlled thereby and acting to operate said breaker when the current in said shunt reaches a certain point.

7. In combination a source of supply, a storage battery, a circuit-breaker, having a magnet in series with said battery and the supply-circuit and acting to operate the breaker when the current is abnormal, an electromagnetic device in shunt with said battery a magnet controlled thereby to operate said circuit-breaker when the counter electromotive force reaches a certain point, and a common detent acted upon by the two magnets.

8. In combination a source of supply, a storage battery, a circuit-breaker, having a magnet in series with said battery acting to operate the breaker when the current is abnormal, an electromagnetic device in shunt with said battery, a magnet controlled thereby to operate said circuit-breaker when the counter electromotive force reaches a certain point, said circuit-breaker acting to interrupt the circuits through said electromagnets and electromagnetic device.

9. In combination a source of supply, a storage battery, a circuit-breaker, having a magnet in series with said battery acting to operate the breaker when the current is abnormal, an electromagnetic device in shunt with said battery, a magnet controlled thereby to operate said circuit-breaker when the counter electromotive force reaches a certain point and means for modifying the action of said electromagnetic device to compensate for variations in temperature.
